SPEED CONTROL MECHANISM

Walton W. Cushman, Webb City, Mo.

Original application December 14, 1949, Serial No. 132,961. Divided and this application December 19, 1950, Serial No. 201,669

6 Claims. (Cl. 123—16)

(Granted under the act of March 3, 1883, as amended April 30, 1928; 370 O. G. 757)

1

The invention described herein, if patented, may be manufactured and used by or for the Government for governmental purposes, without the payment to me of any royalty thereon.

This invention relates to speed control mechanisms for engines and particularly internal combustion engines, and is a division of my application Serial No. 132,961, filed December 14, 1949, for Rotary Internal Combustion Engine.

A primary object of the invention consists in the employment of an automatically operated governor which is controlled centrifugally in accordance with the R. P. M. of the rotor shaft throughout a wide range of operation and obviates the need for a conventional butterfly throttle.

A still further object of the invention resides in the provision of a speed control mechanism of simplified construction consisting only of a disc and spring located in the hollow shaft of the engine and directly controlling the flow of fuel to the combustion chamber.

Other objects and advantages of the invention will be apparent from the following description taken in connection with the accompanying drawings, in which,

Figure 1 is a longitudinal sectional view through the rotary internal combustion engine taken on the line 1—1 of Figure 3;

Figure 2 is a fragmentary sectional view taken on line 2—2 of Figure 4;

Figure 3 is a vertical sectional view taken on line 3—3 of Figure 1 (partly in elevation) and looking in the direction of the arrows;

Figure 4 is an end elevational view (partly in section) taken on the line 4—4 of Figure 3 and looking in the direction of the arrows;

Figure 5 is a fragmentary end view of the engine looking in the direction of the arrows 5—5 of Figure 3; and

Figure 6 is a fragmentary sectional view of the butterfly valve and its operating spring.

In the present illustration of the rotary internal combustion engine the stator forms a part of the exterior casing and is of circular construction, and is indicated generally by the numeral 1. Provided on opposite edges of the stator is a pair of bosses 2, to which base members or supports 3 may be secured as by bolts 4 for supporting the engine on a base or the like; al-

2

though it is to be understood that various conventional means may be employed for supporting the engine on a base or for suspending it by means of hangers.

5 The stator includes a disc-like casting 10, provided with a hollow bearing sleeve 11, and provided also with a divider ring 10' having a series of recesses 12 to lighten the structure, and serving to provide lateral bearing surfaces for the rotor, as will appear hereinafter. The rotor is preferably formed of plated aluminum or other lightweight metal as is the stator, but cast iron has been successfully used on a hard steel shaft.

The shaft of this engine, in the present illustration is hollow and is indicated by the numeral 13. This shaft is rotatably mounted in the bearing 11 of the stator, and is provided with an annular series of openings 14, positioned just beyond the inner end of the bearing 11, so as to provide for the centrifugal discharge of live fuel into the interior of the engine as will appear later. Fixed to the outer end of the shaft 13, is the rotor 15, comprising a disc-portion 16, concentrically arranged on the shaft 13, as by means 15 of the concentrically located hub 17. Integrally formed on the innerface of the concentric disc 16, but eccentrically thereof, are inner and outer relatively concentric sleeves 18 and 19 having a width corresponding to the width of the divider ring 10' on the stator 10, so that the innerface of the disc 16 bears against the adjacent edge of the divider ring as indicated at 20 and the free ends of the concentrically arranged sleeves 18 and 19 bear against the innerface of the disc-like portion of the stator 10, as indicated by numeral 21. There is thus provided a rotor having an annular hollow portion which cooperates with the stator or divider ring 10' to provide compression and combustion chambers as will later appear. It is to be noted that the hub 17, which is fixed to the rotary shaft 13, is of such length as to provide an annular space between it and the inner end of the bearing 11, so as to provide an annular passageway 22 for the exit of fuel through the openings 14 in the shaft.

40 The piston for the rotary engine is indicated by the numeral 23 and is provided with arcuate sides 24, adapted to be seated for oscillation in similarly curved bearing pads 25, which are 40 mounted for reciprocation radially from the axis

of rotation of the stator divider ring 10'. By means of the reciprocally movable bearing pads, the piston is allowed to oscillate and radially reciprocate to the extent required by the passage of the eccentrically arranged rotor, it being noted that the inner and outer faces 26 and 27 of the piston are curved to correspond to the curvature of the inner and outer sleeves of the rotor.

By reason of this eccentric mounting of the rotor it will be apparent that a combined induction and compression chamber 28 is provided as well as a combined combustion and exhaust chamber 29. To provide for the passage of compressed gases from the compression chamber 28 to the combustion chamber 29, the piston 23 may be provided with a plurality of passages 30, communicating at their outer ends with the compression chamber and at their inner ends with a pocket 31 extending transversely of the piston and opening into an arcuate transverse slot 32 provided on the innerface of the rotor 15. The piston 30 is also provided with a companion pocket 33 communicating with the inner ends of passages 34 formed at the opposite side and end of the piston and communicating with the combustion chamber 29. With this arrangement, the pocket 31 through the medium of the passage-way 30, is always open to the reception of gases from the compression chamber, but such gases cannot be transferred from the pocket 31 to the pocket 33, and thence to the combustion chamber 29, until such time as the forward end of the arcuate slot 32 in the rotor passes the wall dividing these two pockets, such wall being indicated by the numeral 35. From the time that the front end of the slot 32 passes the dividing wall 35 between pockets 31 and 33 and until the trailing end of the slot passes beyond the pocket 31, the gases compressed in the compression chamber are forced into the combustion chamber 29. The gases are ignited at each revolution of the engine, and in this sense, this rotary engine is of the two-cycle type, but in another sense, provides four-cycle performance with complete scavenging after each explosion. To ignite the gases periodically, during each revolution of the engine, a glow plug 36 is provided and is positioned as indicated, (Fig. 2) so that the gases will not be fired in the combustion chamber until after the trailing end of the transfer slot 32 passes the partition 35 in the piston 23, thereby avoiding any possibility of the flames being carried into the compression chamber. In other words, the glow plug will be exposed to the live gases only when the rotor has moved around to such point that the adjacent part of the sleeve 19 passes below the plug so that the latter is actually within the combustion chamber. The timing of the engine may be controlled therefore by varying the radial position of the plug.

As already indicated, the fuel entering the hollow shaft is thrown by centrifugal force through the openings 14, into the interior of the rotor as defined by the inner sleeve 18, and generally indicated by the numeral 37. This inner sleeve 18 is provided with a plurality of openings 38, extending through its wall and just behind these openings a combined scoop and impeller 39 may be provided for imparting a highly turbulent whirling action to the gases passing through the openings 14, and thereby causing them to be thrown by centrifugal force through the openings 38 into the induction and compression chamber 28. At relatively high speeds the gases may be thrown through the

openings 38 by such centrifugal force as to provide an intake charge having a pressure greater than atmospheric. Also, at relatively slow speed, the gases are inducted into the chamber 28 by the vacuum created therein, the amount of centrifugal force at such speed being relatively slight. Because of this centrifugal force, the engine is supercharged in the sense that the pressure of the gases forced into the chamber 28 is above atmospheric pressure, depending upon the speed. The outer sleeve 19 is provided with a series of exhaust openings 40, through which the exhaust gases are discharged also by centrifugal force tending to reduce the noise, and eliminate all back pressure on the exhaust stroke.

Threaded to the left-hand end (Figure 3) of the hub of the stator 10, as indicated by numeral 41, is the manifold 42, to which the carburetor 43 is connected. Also associated with the outer end of the hub of the stator 10 is a thrust-bearing 44, held in position by a nut 45, threaded to the outer end of the hollow shaft 13, and it is to be noted that this nut is threaded onto the shaft in a direction opposite to the direction of rotation of the rotor so that the inertia of the nut will serve to draw the rotor into closed relationship to the disc-like element 10 of the stator thereby automatically taking up any wear caused by the frictional engagement in the bearing surfaces 20 and 21 (Figure 3).

Mounted for pivotal movement within the shaft 13, as by means of pin 46, is a butterfly valve 47. In the specific construction illustrated the pin 46 is longitudinally slotted (Figure 6) and the valve 47 is disposed in the slot so that its center is at one side of the pin. A tension spring 48 has an elongated portion 48' extended through the center of the valve and is then secured to the valve in the manner indicated. By this construction any whipping action of the spring which might otherwise be caused by the rotation of the shaft, is avoided. The spring 48 extends through the manifold 42 and the outer end of the spring passes through a central opening in a bolt 49, which is threaded into the closed end 50 of the manifold 42. The outer end of the spring means 48 may be provided with a cone-bearing 51 so that it may readily rotate with respect to the bolt 49 as the hollow shaft 13 is rotated during the operation of the engine. The tension of the spring means 48 is so applied to the pin 46 and butterfly valve 47 as to normally bias the valve to open position, and the centrifugal force caused by the rotation of the shaft tends to move the valve 47 to closed position so that the valve and related parts act as a governor to maintain the engine at a predetermined speed. By adjusting the bolt 49 the amount of tension applied to the pin and butterfly valve may be varied so as to vary the speed of the engine, as desired. The opposite end of the rotary shaft 13 is solid and may have applied thereto a pulley 52 or other power take-off means. In the present illustration, the pulley 52 by means of a keyway or similar device serves to interlock the rotary hub 17 with the shaft 13 and a nut 53 is threadedly connected to this end of the shaft to maintain these elements in interlocked relationship.

That portion of the rotary shaft 13, which is inclosed by the bearing 11 may be provided with oil holes or the like 54 which may be supplied from any suitable source, as is the thrust-bearing 44. One method of supplying oil to the moving parts consists in the use of a moderate amount of oil contained in the air and gasoline

mixture passing into the interior of the rotary shaft, and this oil automatically finds its way through the oil apertures 54 to the several parts requiring lubrication.

The engine illustrated herein is air cooled and for this purpose the stator 10 is provided with a casing 55 having an air outlet 55', while the rotor 15 is provided with a casing 56 fixed to rotate therewith and this casing as well as the casing 55 serve to provide air passages around such elements. The casing 56 is provided with an annular entrance opening 57 and a series of fins or vanes 58 are mounted between the body of the rotor 15 and the inner wall of the casing 56, and these vanes serve as impellers in drawing large quantities of air through the annular opening 57. Likewise, the casing 55 is provided with radially extending fins or vanes 55''. The air entering the casing between the vanes 58 passes about the outer surface of the rotor and about the disc-like portion 10 of the stator and thence out through the discharge opening 56 in the casing 55. It will thus be seen that provision is made for pumping large quantities of cooling air entirely about the exterior of the engine, so as to maintain it at a relatively low temperature. Internal cooling is effected by the incoming gases.

The operation of the engine has been fairly well described in connection with the description of the several parts thereof. It may be well, however, to briefly describe a complete cycle of operation of the several elements as they relate to each other. Assuming that the screw bolt 49 has been adjusted to produce the desired tension in the spring means 48 so as to cause the governor 47 to maintain the engine speed at the desired R. P. M. and electric current sent through the flow plug 36, the engine may be started in any preferred manner such as a coiled rope associated with the shaft 13 or by a blank cartridge placed in the combustion chamber 29.

The rotation of the rotor about the stator causes the formation of the induction and compression chamber which is somewhat smaller than the combustion chamber, thus allowing for more complete expansion of gases prior to the discharge of the exhaust to the atmosphere. The unburned gases are drawn by suction through the openings 14 over the shaft 13 into the compartment 37 which is encircled by the sleeve 18 of the rotor. From thence the gases are drawn through the openings 38 of the sleeve 18 into the compression chamber 28 of the engine. The continued rotation of the rotor decreases the size of the chamber, thus applying pressure to the gases prior to their transfer and entrance into the combustion chamber 29. These compressed gases pass into passageways 30 of the piston 23 and into the pocket 31 thereof. However the transfer of the compressed gases to the combustion chamber 29 cannot take place until the leading end of the transfer slot 32 passes the partition 35 between the two pockets 31 and 33. As soon as the leading end of the slot 32 passes the partition 35 the gases pass into the combustion chamber 29 and continue to be forced into this chamber until such time as the trailing end of the transfer slot 32 arrives at the partition 35. Communication between the combustion chamber 29 and the fuel chamber 37 is automatically cut off at this point because of the position of the rear end of the slot 32 with respect to the partition 35, and it is at this point that the glow plug is exposed to the gases and explodes or

burns them within the chamber 29. It is the expansion of these gases which acts against the relatively fixed piston 23 and related parts of the stator and rotor to give a torque impulse to the rotor. As the speed of the engine increases the centrifugal force caused by its rotation progressively and gradually closes the valve-governor 47 until the engine stabilizes at a speed for which the spring 48 is adjusted. During this increased speed of the engine centrifugal force comes into play to augment the suction heretofore referred to and throws the gases through the openings 14 of the shaft 13, and additional centrifugal force is applied to the gases by reason of the whirling action imparted to them by the rotation of the sleeve 18 and the whirling action may be increased by the employment of the scoop-impeller 39. The gases will thus be forced out through the outlets 38 into the induction and compression chamber 28, and as heretofore referred to are then forced into the combustion chamber at pressures substantially above atmospheric. The exhaust gases pass out through openings 40 in the sleeve 19, and their passage is augmented by centrifugal force. Since there is only a very small reversal in the mass of moving parts, relatively high compression ratios have been used (11:1) without detonation. This cycle of operation is of course rapidly repeated throughout the continuation of the operation of the engine.

The structural features of the engine are claimed in my earlier application identified above, and the claims of this divisional application are limited to the mechanism for controlling the engine speed automatically through the medium of the spring-operated valve 47 which is located in the hollow shaft 13 and therefore adapted to be biased toward closed position by centrifugal force.

In accordance with the patent statutes, I have described what I now consider to be the preferred form of automatic engine control, however, it is to be understood that the present disclosure is intended as illustrative of the invention rather than in any limiting sense, and that the control mechanism may be incorporated in various other types of rotary engines than that disclosed herein.

I claim:

1. A rotary internal combustion engine including a hollow rotary shaft; a fuel supply communicating with one end of the hollow shaft, a valve in said shaft adapted to be closed by centrifugal force, and a spring for biasing said valve to open position.

2. A rotary internal combustion engine including a hollow rotary shaft, a butterfly valve in said shaft, a pin extending transversely of the shaft and pivotally mounting the valve, and a spring for biasing the valve to open position.

3. A rotary internal combustion engine including a hollow rotary shaft, a pin extending transversely of the shaft, a butterfly valve eccentrically mounted on the shaft, and a spring for biasing the valve to open position.

4. A rotary internal combustion engine including a hollow rotary shaft, a fuel supply casing associated with an open end of the shaft, a butterfly valve mounted in the shaft, spring means connected to the butterfly valve and extending to the exterior of the casing, and means for adjusting the tension of said spring.

5. A rotary internal combustion engine including a hollow rotary shaft, a fuel supply casing associated with an open end of the shaft, a butterfly valve mounted in the shaft, spring

7
means connected to the butterfly valve and extending to the exterior of the casing, and a bolt on the exterior of the casing for adjusting the tension on the spring.

8.6. A rotary internal combustion engine including a hollow rotary shaft, a fuel supply casing associated with an open end of the shaft, a butterfly valve mounted in the shaft, spring means connected to the butterfly valve and extending to the exterior of the casing, a bolt threaded to said casing and provided with an axial passage, through which a portion of the spring means extends; and a bearing fixed to the outer end of

8
the spring means and bearing upon the outer face of the bolt.

WALTON W. CUSHMAN.
